CLAIM

I claim the ornamental design for an adhesive back hanger, as shown and described.

DESCRIPTION

This application has some relation to applicant's co-pending applications Ser. No. 29/119,670, filed Mar. 3, 2000, and Ser. No. 29/119,615, filed Mar. 6, 2000.

FIG. 1 is a front perspective view of an adhesive back hanger showing my new design, with the release paper curled up for removal to expose the adhesive;

FIG. 2 is a reduced scale back elevational view thereof;

FIG. 3 is a front elevational view thereof;

FIG. 4 is a top plan view thereof;

FIG. 5 is a bottom plan view thereof; and,

FIG. 6 is a right side elevational view thereof, the left side elevational view being the mirror image thereof.
